UNITED STATES PATENT OFFICE.

RALPH C. IDONE, OF CLEVELAND, OHIO.

CLASP.

1,249,406.

Specification of Letters Patent. Patented Dec. 11, 1917.

Application filed August 4, 1917. Serial No. 184,876.

To all whom it may concern:

Be it known that I, RALPH C. IDONE, a citizen of the United States, residing at Cleveland, in the county of Cuyahoga and State of Ohio, have invented certain new and useful Improvements in Clasps, of which the following is a specification.

My invention relates to improvements in clasps, and more particularly to that class or type known as "garment clasps," the present embodiment of the invention being particularly designed and adapted for use in connection with garters in the attachment and support of hosiery.

The primary object of the invention is to provide a generally improved device of this class which will be exceedingly simple in construction, cheap of manufacture, and efficient in use.

A further object of the invention is the provision of an improved article engaging tang or hook particularly adapted to enter between the meshes of the knit fabric to be supported, as a stocking, or the like, and embodying improved means for preventing the accidental disengagement of the garment clasp when inserted and attached.

A still further object is the provision of an improved tang or hook having an enlarged friction bearing body portion spaced from and extending in a common plane at one side of the clasp plate and having an angular or upturned tip portion extending toward the clasp plate so as to prevent any scratching or possible injury to the flesh of the wearer while in use.

With the above mentioned and other ends in view, the invention consists in the novel construction, arrangement, and combination of parts, hereinafter described, illustrated in one of its embodiments in the accompanying drawings, and particularly pointed out in the appended claims.

Referring to the drawings, forming a part of this specification, Figure 1, shows the improved clasp as applied to and in use in connection with a special form of garter.

Fig. 2, a view of the inner sides of the garter and clasps, detached.

Fig. 3, an edge view of the same.

Fig. 4, a perspective view of one of the clasps, detached.

Fig. 5, an enlarged longitudinal sectional view of one of the article engaging tangs and the adjacent portion of the clasp plate.

Similar numerals of reference designate like parts throughout all the figures of the drawings.

The improved clasp comprises a suitable clasp plate or shield 1, of any suitable and convenient form, and may be attached to an elastic web member 2, in any suitable and convenient manner, as for example, by means of clamping and attaching wings 1^a.

The clamp plate 1, is provided with a plurality of article engaging tangs each comprising an enlarged friction bearing portion 1^b, spaced from and extending in a common plane at one side of the clasp plate as shown most clearly in Figs. 3, and 5, of the drawings, and as a means of more effectively preventing the accidental displacement or detachment of the article engaging tangs while in use, the friction bearing body portion 1^b, is formed to provide enlarged anchor portions 1^c, at the sides, said rounded shoulder or anchor portions 1^c, terminating at their rear in a reduced or neck portion 1^d.

The body portion 1^b, terminates at its front in a tapered pointed portion 1^e, and as a means of preventing the latter from coming into direct contact with the skin of the wearer when in use the tip of the tapered body 1^e, is upturned and extends at an angle from the plane of the body portion 1^b, and toward the clasp plate 1, as shown most clearly in Figs. 3, and 5, of the drawings. The point or tip portions 1^e, are preferably of rounded or dull form so as to more effectively enter between the meshes of the fabric of the article to be supported and the meshes of the article are adapted to spread out over the anchor or shoulder portions of 1^c, and after passing the latter, to again become contracted about the neck portions 1^d, so that the rounded or enlarged portions 1^c, will prevent the accidental displacement of the tangs and at the same time permit of the manual disengagement of the latter from the fabric when desired in detachment.

From the foregoing description, taken in connection with the accompanying drawings, the operation and advantages of my invention will be readily understood.

Having thus described one of the embodiments of my invention, what I claim and desire to secure by Letters Patent, is,

1. A garment clasp, comprising a plate member provided with article engaging

tangs each comprising a pointed portion terminating in enlarged laterally extending rounded anchor portions.

2. A clasp, comprising a clasp plate provided with struck out article engaging tangs having enlarged frictions bearing body portions spaced from and extending in a common plane at one side thereof and having upturned tips extending toward said clasp plate.

3. A clasp plate provided with article engaging hooks extending in a common plane

at one side and each having oppositely located enlarged portions terminating in neck and pointed portions, said pointed portion being bent inwardly at an angle to the plane of the body of the hook and extending toward said clasp plate.

In testimony whereof I have affixed my signature in the presence of two witnesses.

RALPH C. IDONE.
